(57) **CLAIM**

The ornamental design for a LED work light, as shown and described.

DESCRIPTION

FIG. 1 is a front perspective view of a first embodiment of a LED work light, showing my new design;
FIG. 2 is a rear perspective view thereof;
FIG. 3 is a top plan view thereof;
FIG. 4 is a front elevation view thereof;
FIG. 5 is a bottom plan view thereof;
FIG. 6 is a right elevation view thereof, the left elevation view being a mirror image thereof; and,
FIG. 7 is a rear elevation view thereof.

The broken lines shown in the drawings depict portions of the LED work light that form no part of the claimed design.
